WILLIAM M. K. THORNTON, OF CLINTON, WISCONSIN.

Letters Patent No. 89,836, dated May 4, 1869.

IMPROVED BUCKLE.

The Schedule referred to in these Letters Patent and making part of the same.

To all whom it may concern:

Be it known that I, WILLIAM M. K. THORNTON, of Clinton, in the county of Rock, and State of Wisconsin, have invented a new and useful Improvement in the Manufacture of Buckles; and I do hereby declare that the following is a full, clear, and exact description thereof, reference being had to the accompanying drawings, making part of this specification, in which—

Figure 1 is a perspective view of the improved buckle, having a trace and ring-strap applied to it, and having its stud or tongue in the middle of its length.

Figure 2 is a front view of the improved buckle.

Figure 3 is a longitudinal section, taken centrally through the buckle.

Figures 4, 5, and 6, are views of my improved buckle, constructed with the stud or tongue on one of its end-bars.

Similar letters of reference indicate corresponding parts in the several figures.

This invention relates to certain novel improvements on the buckle for which Letters Patent of the United States were granted to me, on the 3d day of September, 1867, the object of which improvements is to facilitate the manufacture of the buckles, and not only render them stronger and lighter, but give to them a handsomer appearance than hitherto, without departing from the general features and advantages described in the schedule annexed to said Letters Patent.

The patented buckle above referred to has its side-loops and intermediate cross-bar arranged at or near the middle of the width of flat side-bars, which arrangement requires great care in casting, to obviate flaws, and also requires the finishing to be done with hand-files.

To obviate these and other objections attending such arrangement of loops and cross-bar, the nature of my invention consists in constructing and arranging the side-loops in such manner that their front or exposed faces are in the plane of the front or exposed edges of the side and end-pieces of the buckle, and in constructing the said side-pieces with flanges upon their outer sides, for strengthening them, and, at the same time, presenting a large surface for ornamentation, and hiding from view those surfaces which it is not desired to polish; also, in arranging the intermediate tug-bar as near as possible to the back edges of the side-bars, for the purpose of producing this bar without flaws at the junctions with its side-bars, all as will be hereinafter explained.

To enable others skilled in the art to understand my invention, I will describe its construction and operation.

The buckle which I have represented in the drawings consists of two parallel side-bars, *c c*, united at their extremities by flat cross-bars, *b b*, upon one of which a loop or eye, *A*, is formed.

At an intermediate point between the cross-bars *b*, and extending transversely across from one of these

bars to the other, is a cylindrical bar, *d*, to which the hames or tug-strap is attached, and from which extends a tongue or stud, *e*, for entering one of many holes made through the trace, and forming the attachment for the same.

Instead of having the tongue or stud *e* formed on the bar *d*, it may be formed on the inner side of one of the flat cross-bars *b*, as shown in figs. 4 and 5.

The bars *c c* also have side-loops *ff*, formed on their outer sides, as shown in the drawings.

Thus it will be seen that, in several respects, the buckles shown in the drawings represent the buckle which was secured to me by Letters Patent in the year 1867, above referred to.

The differences are these:

First, I arrange the oblong side-loops *ff* so that their outer surfaces are in the plane of or flush with the corresponding outer surfaces, *a*, of the side-bars *c c* and cross-bars *b b*, thus making the outer surface of the buckle present a smooth or unbroken surface, except loop *A*, which is slightly turned outward.

Thus it will be seen that the surface or surfaces *a*, which are exposed to view when the buckle has applied to it its straps, can be conveniently dressed and polished, or plated, owing, as above stated, to the unbroken surfaces thus presented.

It will be seen, by reference to the two figs. 3 and 6, that the surfaces *a* are curved or made convex, both in a direction with the length and width of the buckle.

The side-bars *c c* are strengthened by forming flanges, *i i*, along their sides, externally, which not only increase the thickness of these bars in the plane of the surfaces *a*, and present a very neat appearance, but they give the bars, in cross-section, the shape of the letter *L*, which adds great strength to them, and prevents the buckles from warping while being annealed.

From the flanges *i i*, the bars are tapered inward, and their inner edges are very acute. Thus I dispose the metal so as to obtain the greatest strength where most needed, and produce a very light buckle, which not only presents the external appearance of great strength, but which is really stronger than buckles of a corresponding size which I have hitherto produced.

The inner sides of the bars *c c*, against which the tug-strap and trace abut, are flat, and parallel to each other, and perpendicular, or nearly so, to the inner surfaces of the flat cross-bars *b b*.

The round tug-bar *d*, which, in my patented buckle above referred to, is at, or nearly at the middle of the width of the thin side-bars, is, in this improved buckle, arranged as near the inner edge of the swelled portions of the bars *c c*, for two reasons, viz., that there shall not be any more metal in these bars than is absolutely necessary to obtain the requisite degree of strength and width of side-bars, and also that this bar *d* may be cast with the buckle without having flaws or weak points at its junctions with its side-bars.

In casting the old form of buckles above referred to, the moulding-sand in the sectional flask parts in a plane with the tug-bars; consequently it is almost im-

possible to make perfectly solid castings in all parts, and, where the greatest strength is required in the old buckles, they are frequently found to be weakest.

It will be seen, from the above description, that my improved buckle can be conveniently dressed or finished by the use of emery-wheels, or other polishing and grinding-surfaces, and that very little labor is required to finish them, either by grinding, plating, or otherwise, as only the surfaces *a* are exposed to view when the buckles are in use, the flanges *i* serving to hide from view those parts which may not be finished.

Having described my invention,

What I claim as new, and desire to secure by Letters Patent, is—

An improved article of manufacture, consisting of a buckle, having its side-bars *c c* flanged, and its side-loops *f f* arranged so that their outer surfaces *a* are flush with the corresponding surface *a* of said bars and their cross-bars *b b*, as herein set forth.

WM. M. K. THORNTON.
